[57] CLAIM

The ornamental design for a video camera with LCD monitor, as shown and described.

DESCRIPTION

FIG. 1 is a rear elevational view of a video camera with LCD monitor according to our design;

FIG. 2 is a front elevational view thereof;

FIG. 3 is a bottom plan view thereof;

FIG. 4 is a top plan view thereof;

FIG. 5 is a left side elevational view thereof;

FIG. 6 is a right side elevational view thereof;

FIG. 7 is a top, front and right side perspective view thereof with the lens turned in a forward direction;

FIG. 8 is a top, rear and left side perspective view; and,
FIG. 9 is a top, rear and left side perspective view with the lens turned in a rearward direction.

Applicants hereby disclaim the written material shown in the drawing figures as such written material forms no part of the present design.
